UNITED STATES PATENT OFFICE.

ANGELO BUCCIARELLI, OF CHAPLEAU, ONTARIO, CANADA.

WRENCH.

Application filed January 29, 1924. Serial No. 639,297.

This invention relates to improvements in combination wrenches and particularly that type which embodies a hammer and nail-pulling device.

An important object of the invention is to provide a device which combines a wrench and hammer head to be utilized for many different purposes.

A further object of the invention is to provide a device of this character which may be conveniently transported.

A further object of the invention is to provide a device of this character which is comparatively simple yet durable of construction and efficient for the purpose intended.

In the accompanying drawing forming a part of this specification and in which like numerals are employed to designate like parts throughout the same:

20 Figure 1 is a side elevation of the device, Fig. 2 is a top plan view of the same,

Fig. 3 is a vertical sectional view taken on the line 3—3 of Fig. 1, and

25 Fig. 4 is a similar view taken on the line 4—4 of Fig. 1.

In the drawing, wherein for the purpose of illustration is shown the preferred embodiment of my invention, the numeral 5 designates a rectangular bar or shank which 30 serves as the body of the device, one extremity of the body or shank 5 being partially covered by a handle 6, which is secured to the body by means of a screw 7 or the like, and is constructed of wood or any desirable material. Formed integral with the forward portion of the body bar or shank 5 is a hammer head, generally denoted by the numeral 8, the body of said head being somewhat heavier than the body bar or shank 5 and having the usual nail-contacting projection 9 formed on the lower portion, the inner 35 face of the nail contactor 9 having a plurality or row of gripping teeth 10 formed thereon. The upper portion of the hammer head 8 has a pair of curved claw members 11 formed thereon, said claws having a tapered slot 12 formed therebetween and adapted to engage the heads of nails or the like.

40 A guide bracket 13 is pivotally secured to the body bar or shank 5 at a point between the ends thereof and at a point spaced from the fixed jaw and the row of teeth thereon, by means of a rivet 14, the pivot of the bracket being located at a point between the median longitudinal dimension of the shank 45 and that edge of the shank adjacent the row

of teeth 10, the bracket 13 having a band portion disposed around the opposite side edge of the bar or shank 5. The bracket 13 is adapted to carry an adjustable shank 15, 60 which is practically rectangular in cross-section and is provided with threads 16. The forward portion of the shank 15 has a jaw 17 formed thereon, said jaw being of somewhat heavier construction than the shank 65 and having a plurality of gripping teeth 18 formed on the forward face thereof. The movable jaw 17 is located between the row of teeth 10 on the fixed jaw 9 and the bracket 13, and the side edge of the movable jaw 17 being arranged for bearing against the side 70 surface of the bar or shank 5 at a point between the fixed jaw and bracket.

In order to permit adjustment of the shank 15 and the jaw 17 carried thereby, an 75 internally threaded ring or nut 19 is positioned or journaled in a slot or opening 20 formed in the guide bracket 13 and engages the external threads 16 of the shank 15, the outer face of the ring 19 having a nubled 80 surface in order to enable the ring to be firmly grasped between the fingers.

In use, it is obvious that adjustment of the shank 15 will cause movement of the jaw 17 in contact with or away from the toothed 85 face of the hammer head 9, thereby permitting various-sized objects to be retained between the movable jaw 17 and the toothed face of the hammer head. In addition to this use, the device may obviously be employed as a hammer, the head 8 being constructed to withstand such application.

It is also to be noted that the claws 11 formed in the upper portion of the hammer head greatly enhance the utility of the device, as the necessity for such a tool is well known to those familiar with the mechanical art.

It is to be understood that the form of my invention herewith shown and described is 100 to be taken as the preferred example of the same, and that various changes in the shape, size, and arrangement of parts may be resorted to without departing from the spirit of the invention or the scope of the subjoined 105 claim.

Having thus described my invention, I claim:

A wrench comprising a shank having a fixed head provided with a row of teeth, the 110 row of the teeth being disposed at a right angle to the longitudinal edges of the shank,

a bracket pivoted to the shank at a point between the ends thereof and at a point spaced from the fixed jaw and the row of teeth thereof, the pivot of the bracket being located at a point between the median longitudinal dimension of the shank and that edge of the shank adjacent the row of teeth of the fixed jaw, said bracket having a band portion disposed around the opposite side 5 edge of the shank, a movable jaw having a shank slidably received in the bracket, and

a nut carried by the bracket and engaging the shank of the movable jaw, the said movable jaw being located between the row of teeth of the fixed jaw and the bracket, and the side edge of the movable jaw bearing directly against the side surface of the first-mentioned shank at a point between the fixed jaw and the bracket. 15

In testimony whereof, I have affixed my 20 signature.

ANGELO BUCCIARELLI.
